UNITED STATES PATENT OFFICE.

HARRY H. BURSON, OF CHICAGO, ILLINOIS, ASSIGNOR TO BURSON BROS., OF CHICAGO, ILLINOIS, A COPARTNERSHIP.

STUDDING FOR PLASTER-BOARDS OR THE LIKE.

1,013,738.

Specification of Letters Patent.

Patented Jan. 2, 1912.

Application filed December 5, 1910. Serial No. 595,676.

To all whom it may concern:

Be it known that I, HARRY H. BURSON, a citizen of the United States, residing at Chicago, in the county of Cook and State of Illinois, have invented certain new and useful Improvements in Studdings for Plaster-Boards or the Like, of which the following is a specification.

The present invention relates to a studding more especially adapted to support plaster boards or analogous substances used in the construction of walls.

The objects of the present invention are, to form a simple structure which will be easy of manufacture; to so configurate the structure as to provide a series of crotches in the body thereof, in which the ends of the plaster board will rest; to provide means for maintaining the plaster board in proper position with respect to the studding prior to the application of the plaster; to provide a series of openings in the body of the studding to permit of the ingress of plaster to the interior of the studding, whereby the studding is transformed after the application of plaster into a solid structure; and to form the portions of the studding which lie in the body of the wall of a configuration adapted to withstand pressure.

The invention further consists in the features of construction and the combination of parts hereinafter described and claimed.

In the drawings, Figure 1 is a sectional plan view, showing the studding and plaster board embedded in a completed wall, and showing one means for maintaining the board in place upon the studding prior to the application of plaster; Fig. 2, a view similar to Fig. 1, showing another means for maintaining the plaster boards in position; Fig. 3, a face view of the studding of the present invention; and Fig. 4, a perspective of a section of said studding.

The studding comprises a body portion, which, as shown, is formed of a single piece of sheet-metal and is bent into a cross-like configuration to provide oppositely extending sets of wings 6 and 7. As shown in the drawings, the studding is of a shell-like nature, whereby a hollow interior is provided. The wings 6, as shown, extend out from the body of the studding in a direction longitudinally of the plaster boards, and are

of a substantially rectangular formation in cross section. The wings 7, as shown, extend out from the body of the studding in a direction transversely of the plaster boards and are of a substantially triangular shape in cross section. This triangular formation of the wings 7 is for the purpose of enabling them to resist the strain which will necessarily be brought to bear thereon, which strain will be produced because these wings, as shown, lie in the body of the wall and the pressure which is exerted against the faces of the wall is transmitted directly to these wings, and it is a well known mechanical principle that a curved or sloping surface is better adapted to withstand pressure than a flat one. Were it not for the additional strength which is thus given to these walls, these wings 7 might properly be formed of a rectangular configuration the same as the wings 6. So far as the function of these wings 7 in maintaining the ends of the plaster board is concerned, they could be formed either square or sloping; but by forming the walls of these wings sloping, the positioning of the plaster boards upon the studding is rendered easier, since the distance between the outer edges of the wings 7 is greater than the distance between the inner edges of said wings. This provides for an easy entrance of the boards into position between the studding.

At the intersection of the wings 6 with the wings 7 are formed crotches 8, in which the ends 9 of plaster boards 10 rest. The crotches formed at the juncture of the wings would, in the construction shown, be four in number, two of them lying upon either side of the center of the studding. This provides a means for placing plaster boards upon opposite sides of the studding, whereby a hollow wall construction can be produced, the wings 6 serving to space the plaster boards apart and permit of a channel between them.

The wings 7 have a series of cuts along their outer edge, which are of a nature to form tines 11 along said edge. These tines are adapted to be bent into the position shown in Fig. 1, and when so bent serve as means for retaining plaster boards in position prior to the placing of plaster thereupon. The cutting of the wings 7 to form these tines produces a series of openings 12

along the edge thereof, through which openings the plaster percolates during the construction of the wall and enters into the interior of the studding. The wings 7 are 5 further provided with holes 13 located in each wall of said wings and in alinement with one another; and through these openings a member 14 may be inserted, said member being in the nature of a nail or 10 other analogous article. And this member 14 will serve as a means for securing the ends of the plaster boards in position when it is not desirable to bend the tines 11 into position to fulfil this purpose. When the 15 studding is formed with both the holes 13 and the tines 11, the user may choose which of these means be desires to utilize to perform this work, but, of course, it is evident that the studding may be formed only with 20 the holes 13, and with the tines 11 eliminated, or vice versa.

In practice the device is used as follows: The studdings are placed at predetermined intervals at the points where the wall is to 25 be erected. The plaster boards are then inserted in position. This is accomplished by simply laying them on top of one another with their ends resting within the crotches 8. As they are placed with their 30 ends in this position, then, with the form of studding shown, either the tines 11 are bent into the position shown in Fig. 1 to maintain the boards in proper position with respect to the studding before plaster is 35 applied thereto, or a member 14 is inserted through the holes 13 to accomplish this result, the manner of securance being entirely optional with the user. After the 40 plaster boards have been positioned upon the studding, plaster is applied to the outer surface of the boards to form a complete wall, and during such application the plaster will percolate into the interior of the 45 studding to form the studding into a solidified mass in place of the original shell-like structure.

It will be noted that the wings 7 project beyond the outer faces of the plaster board, so that when the plastering is applied it 50 will readily enter through the openings 12 into the interior of the studding.

I claim:

1. A studding of the class described, formed of a piece of metal bent to provide 55 a shell-like structure cross-shaped in section and consisting of wings, the juncture of the wings providing crotches in which the ends of the plaster board rest, one set of wings being rectangular in cross section, 60 and the other set of wings being triangular in cross section, the rectangular wings being located between the triangular wings, and means for securing the ends of the plaster board in place upon the studding prior 65 to the application of the plaster thereto,

the body of the studding being provided with openings to permit of the ingress of plaster thereto, substantially as described.

2. A studding of the class described, formed of metal bent to provide a shell-like 70 structure cross-shaped in section having oppositely extending wings, the wings coöperating to provide crotches at their juncture in which the ends of the plaster board rest, and tines struck from the body portion of one set of wings, adapted to secure the ends of the plaster board in position prior to the application of the plaster thereto, substantially as described.

3. A studding of the class described, 80 formed of metal bent to provide a shell-like structure cross-shaped in section having oppositely extending wings, the juncture of the wings providing crotches in which the ends of the plaster board rest, one set of 85 wings being rectangular in cross section, and the other set of wings being triangular in cross section, the rectangular wings being located intermediate the triangular wings, and tines struck from the body portion of one set of wings, adapted to secure the ends of the plaster board in position upon 90 the studding prior to the application of the plaster thereto, substantially as described.

4. A studding of the class described, 95 formed of metal bent to provide a shell-like structure cross-shaped in section having oppositely extending wings, the wings coöperating to provide crotches at their juncture in which the ends of the plaster board rest, 100 one set of oppositely disposed wings projecting beyond the ends of the plaster board, and members carried by the body of said set of wings projecting outwardly therefrom and serving to secure the ends of the 105 plaster board in place prior to the application of the plaster, substantially as described.

5. A studding of the class described, formed of metal bent to provide a shell-like 110 structure cross-shaped in section having oppositely extending wings, said wings coöperating to provide crotches at their juncture in which the ends of the plaster board rest, one set of oppositely disposed wings projecting beyond the ends of the plaster board, and members carried by said oppositely disposed 115 wings and projecting outwardly therefrom and serving to secure the ends of the plaster board in place prior to the application of the plaster, the body of the studding being provided with openings to permit the ingress of the plaster thereto, substantially as described.

6. A studding of the class described, 125 formed of metal bent to provide a shell-like structure cross-shaped in section having oppositely extending wings, the wings coöperating to provide crotches at their juncture in which the ends of the plaster board rest, 130

one set of oppositely disposed wings having
a series of tines struck therefrom for main-
taining the plaster boards in position prior
to the application of the plaster, the open-
5 ings produced by the forming of the tines
providing means for permitting the ingress

of the plaster into the body of the studding,
substantially as described.
